DESIGN FOR A CARPET.

SPECIFICATION forming part of Design No. 15,467, dated October 14, 1884.

Application filed June 30, 1884. Term of patent 3½ years. Patented in England February 22, 1884, No. 2,300.

To all whom it may concern:

Be it known that I, HORATIO SMITH, a resident of Kidderminster, England, have invented and produced by my own genius, efforts, industry, and expense a new and original Design for a Carpet, of which the following is a full description, in connection with accompanying photograph, which represents a face view of my new design for a carpet.

10 This invention relates to a new ornamentation of the face of a carpet, oil-cloth, or analogous fabric.

15 In the accompanying photograph are represented the various parts which enter into my new design. The stripe A is composed of a band, a, with ornamentation thereon composed of conventional flowers starting from a row of ornaments of heart shape. The stripe A also contains the band b, ornamented by the representation of deeply-serrated leaves and flowers somewhat resembling those of the anemone, and the ornamental band c. The part B contains the rosette d, from which extend the 20 branches e, g, h, and i. The branch i carries 25 the flower d', having a special set, j, of lower leaves. The branch e is a serrated leaf. The branch g carries flowers d', having special sets of lower leaves, j, and also serrated leaves e' and buds f. The branch h also carries flowers d', j, and leaves e'.
